UNITED STATES PATENT OFFICE.

DANIEL ANTON ZURBRIGG, OF MILFORD, DELAWARE, ASSIGNOR TO THE L. D. CAULK COMPANY, OF MILFORD, DELAWARE, A CORPORATION OF DELAWARE.

DESIGN FOR A DENTAL TRIMMING-FILE.

53,958.

Specification for Design.

Patented Oct. 7, 1919.

Application filed May 20, 1918. Serial No. 235,737. Term of patent 14 years.

To all whom it may concern:

Be it known that I, DANIEL ANTON ZURBRIGG, a subject of the King of Great Britain, residing at Milford, in the county of Sussex, State of Delaware, have invented a new, original, and ornamental Design for a Dental Trimming-File, of which the following is a specification, reference being had to the accompanying drawing, in which—

Figure 1 is a view in perspective of a dental trimming file embodying my new design.

Copies of this patent may be obtained for five cents each, by addressing the "Commissioner of Patents, Washington, D. C."

Fig. 2 is a view in perspective of the same, the file being turned about its axis through an angle of 180° from the position of Fig. 1.

I claim:

The ornamental design for a dental trimming file, as shown.

DANIEL ANTON ZURBRIGG.
